UNITED STATES PATENT OFFICE.

THOMAS S. WILES, OF ALBANY, NEW YORK.

MAGAZINE FOR PHOTOGRAPHIC CAMERAS.

SPECIFICATION forming part of Letters Patent No. 423,649, dated March 18, 1890.

Application filed December 21, 1888. Serial No. 294,269. (No model.)

To all whom it may concern:

Be it known that I, THOMAS S. WILES, a citizen of the United States, residing at Albany, in the county of Albany, State of New York, have invented certain new and useful Improvements in Magazines for Photographic Cameras, of which the following is a specification, reference being had therein to the accompanying drawings.

This invention has relation to magazine plate-holders for photographic cameras; and it has for its objects the provision of a magazine capable of holding a number of plates and permitting the successive exposure of the same without requiring a construction which involves a part projecting beyond the outlines of the camera-back and a magazine which is not only adapted for the storage, delivery for exposure, and reception after exposure of sensitized plates of glass, but also of photographic films when mounted on paper, zylonite, celluloid, or any other thin base, whether flexible or otherwise.

Other objects and advantages of the invention will appear in the following description, and the novel features thereof will be particularly pointed out in the claims.

The present tendency of the art being the employment of thin flexible bases for the sensitized film made on paper, zylonite, celluloid, insoluble gelatine, and other substances, and the natural tendency of such bases being to curl on account of the strain exerted by the contraction of the film in drying, some means is required to hold the plate, when made of such substances, in a perfectly-flat position during exposure. It has been essayed to overcome this objection by coating both surfaces of the base, intending that the contraction of the coatings on opposite surfaces shall counteract each other. This involves mechanical difficulties and increased cost. It has also been the practice to insert such thin plates in holders or carriers of substantially book form, having a front protecting-rim provided with posterior vertical flanges and a back consisting of a slab of wood or other convenient material to fit within the flanges and retain the film between the back and the front protecting-rim. While such form of carrier answers, practically, the purpose in view when used in connection with ordinary plate-holders, it

is not well adapted to magazines by reason of the excessive thickness thereof. The thinness carrier of the construction above mentioned is three thirty-seconds of an inch, equal to .09375 of an inch, while a holder constructed in accordance with my invention to carry the same film is but .047 of an inch in thickness, a reduction in thickness of .04675 of an inch, substantially one-half, or fifty per cent.

Referring to the drawings, Figure 1 is a partial front elevation of the magazine. Fig. 2 is a horizontal section, on an enlarged scale, of certain details of Fig. 3, the section being taken on the line 1 1 of Fig. 1 and 2 2 of Fig. 4. Fig. 3 is a horizontal section on the line 1 1 of Fig. 1 and line 2 2 of Fig. 2, showing the plate-holder engaged with the front of the magazine. Fig. 4 is a partial elevation of the back of the plate-holder. Fig. 5 is a horizontal section on the line 3 3 of Fig. 4 and 4 4 of Fig. 6, showing the plate-holder engaged with the back of the magazine. Fig. 6 is an elevation of the back of the magazine. Fig. 7 is a horizontal section, on an enlarged scale, taken on the line 3 3 of Fig. 4 and 4 4 of Fig. 6, of certain details of Fig. 5. Fig. 8 is a partial vertical section on the line 5 5 of Fig. 10 of the magazine, showing certain details of the slides in elevation. Fig. 9 is a partial front elevation of the plate-holder. Fig. 10 is an end elevation of the magazine, plate-holder, and part of the back of the camera. Fig. 11 is a partial section of the magazine, taken on the line 6 6 of Fig. 10. Fig. 12 is a partial plan of Fig. 10. Fig. 13 is a vertical section on line 7 7 of Fig. 5. Fig. 14 is a perspective of the plate-receiver. Fig. 15 is a perspective of the metal plate-carrier. Fig. 16 is a perspective of the metal plate-carrier modified. Fig. 17 is a perspective of the follower. Figs. 18 and 19 are perspectives of portions of modified film-carriers, and Fig. 20 is a modified construction of the plate-retaining spring which may be employed with the plate-carrier.

Like letters refer to like parts in all the figures of the drawings.

For clearness of description all surfaces in the direction of the lens are designated as the "front" surfaces, and the opposite surfaces are designated as the "back."

Referring more particularly to Fig. 3, A represents the back frame of a camera, A' a

portion of the bellows, and A² the bellows-frame, these parts being of the usual construction. B represents the plate-holder proper, and in order to adapt it to be applied to any ordinary camera it may be provided with springs B'^x, (see Fig. 13,) which are adapted to enter the opening in the camera-frame and bear upon the inner surface of said frame, thereby retaining the plate-holder 10 from accidental displacement. Any other well-known connecting device may be employed instead of the springs B'^x.

One of the objects in providing the springs B'^x is to adapt the plate-holder B and the 15 magazine hereinafter described to be used in connection with that class of cameras in which the focusing-glass is removably held in position by springs which yield and permit of the interposition of an ordinary plate-holder, 20 said springs then serving the additional function of retaining said ordinary plate-holder in operative position for exposing a plate therein.

When my plate-holder and magazine are to 25 be used in connection with cameras having a hinged focusing-screen, the plate-holder may be attached in any suitable manner to the camera-frame. In fact, my plate-holder may be permanently secured to or formed as a 30 part of the camera-frame.

The plate-holder proper B is rabbeted for 35 the reception of a plate-receiver C, having an exposure-opening substantially agreeing with that of the camera. In this instance, and in order to reduce the thickness of the plate-holder, one wall of the rabbet is formed by attaching a metal plate B' to the front of the plate-holder and allowing it to project inwardly. A spring C' is provided to force the 40 plate-receiver toward the magazine. While the plate B' forms what may be termed the "front" wall of the rabbet, another plate B³ of metal is employed to form the side wall of the rabbet, and it extends throughout the depth 45 of the rabbet.

B³ represents a slide for closing the back of the exposure-opening of the plate-holder.

B⁴ represents the beveled strips in which the slide B³ operates. In this instance the 50 plate B' and the beveled strips B⁴ are secured by rivets passing through them and through the frame-work of the holder. The slide B³, Fig. 13, passes to a point outside of the plate B', and is then bent forward and again laterally beneath its beveled strips B⁴. At the 55 forward angle there is formed on the slide a projection or teat B⁵, and the frame-work of the holder is grooved or rabbeted adjacent to the plate B² to form a passage-way for said projection. The strip B² is bent at its end, as shown at B^{2x}, Fig. 4, to project across the 60 path of the projection B⁵ on the slide, so as to prevent its complete withdrawal. At the side or end opposite that at which the slide is entered and withdrawn the plate-holder frame is provided with a plate B⁶, Fig. 3, which forms the exterior surface of that end of the frame.

This plate is projected beyond the rear surface of the frame, and is provided with dowels B⁷, adapted to engage with holes D', formed 70 in the magazine D, thereby serving the function of retaining the magazine in contact with that end of the plate-holder.

The magazine D comprises a main framework having a continuous opening there-through of a size suited to the plates intended to be stored therein. It is provided with slides D² D³. The exterior surface of its slide-receiving end is formed with projecting ribs D⁴, and the slides are bent to embrace 80 said ribs. A similar rib B^{7x} is formed on the adjacent exterior of the plate-holder, and its slide B³ (see Fig. 12) has secured thereto an angle-plate B⁸, which fits over the rib B^{7x}. Instead of bending the plate B² to form an 85 obstacle for the projection B^{2x} to come in contact with, any other well-known stop may be employed.

The slides D² D³ of the magazine are identical in construction except in the conformation of their entering edges, and they ride in beveled strips D¹⁰, Fig. 13. On the head of each of the slides D² and D³ is mounted a locking device D⁵ for retaining the slide in a closed position. This device may be, as 95 shown, duplicated, so as to lock the slide at opposite edges. It is also further constructed to perform an additional function—namely, to lock the slide upon which it is mounted to the plate-holder slide when the two are placed 100 adjacent to each other in the use of my invention, as hereinafter described. It is apparent that the construction adopted to perform either of these functions may be omitted, and that for performing the remaining 105 function retained—as, for example, when used upon an ordinary plate-holder to retain the slide thereof in a closed position.

The locking device consists of a reciprocative plate D⁵, mounted upon the head of the 110 slide, in this instance by means of headed pins or lugs D⁶, Fig. 10, passing through the slots D⁷, formed in the plate, whereby the same may be reciprocated upon the head. When reciprocated in one direction, an end of the 115 plate D⁵ is projected under an ear D⁸, formed on a plate, which for convenience is in this instance secured to the top and at the end of the frame of the magazine by screws D^{8x}, Fig. 12. This plate is duplicated, as shown, when 120 two locking devices are employed. The locking device or plate D⁵ is provided with a riser D^{5x}, which has projecting therefrom a handle or finger-piece D^{5xx} and a hook or headed rivet D⁹. By reference to Fig. 9 it will be 125 seen that the head of the slide B³ of this plate-holder has a hole B⁸ to receive the head of the hook or rivet D⁹ and a communicating slot B^{8x} to receive the shank of said hook or rivet. The locking end of the hole B⁸ or of the slot B^{8x} in the head of the slide B³ is so disposed as to direction that when the end of the plate D⁵ is in locking contact with the co-operating ears D⁸ on the magazine the latter

may be removed from the plate-holder, and when the locking device or plate D⁵ is out of contact with the ears D⁸ the magazine-slide is securely locked to the slide of the plate-holder. It will be seen that this construction prevents the withdrawal of the magazine-slide D² or D³ until it is firmly locked to the slide B³ of the plate-holder, thus insuring the action of the two slides B³ and D² or D³ and D⁵ as one. It also insures the locking of the magazine-slide before the magazine can be removed from the plate-holder. It is evident that the elements of this locking mechanism may be reversed—that is, the headed rivet or hook may be secured to the head of the plate-holder slide B³, and the engaging-slot may be in the locking-plate. It is also evident that the exact relative disposition of these locking devices may be varied, it being only essential that they be arranged adjacent to each other.

E indicates a series of plates or plate or film carriers in the magazine D.

Within the magazine and back of the series of plate-carriers E there is a spring-follower 25 lower F. This follower is shown in perspective in Fig. 17, and it consists of a sheet-metal or other plate of a size corresponding to that of the plate or film carriers, and preferably not thicker than a film-carrier. This follower 30 is provided with springs F', having the ends chamfered and secured by rivets F², so that an entering slide will not abut against said springs.

The receiver C (see Fig. 14) comprises a frame having an opening C', adapted to register with the opening B' of the holder. The receiver is provided on its rear surface with flanges C², the depth of which flanges is substantially equal to the thickness of one film or plate carrier. The ends of the flanges are beveled, as at C^{2X}, to co-operate with the slides, as hereinafter described. This bevel is shown in Figs. 2, 3, 5, 7, 11, and 14.

It now remains to describe novel and important features of construction and function of the entering edges of the slides B³, D², and D³. These are so constructed as to act in one relative arrangement to force the receiver C and its contained plate into the plate-holder, 50 and in another relative arrangement to eject a plate or film carrier from the receiver and to project it into the magazine. The construction adopted in this instance to embody this mode of operation is now to be described; but 55 the conformation of these edges to adapt them to perform the functions specified may be varied in detail from that shown. The latter is disclosed as one practicable manner of embodying the invention.

60 Referring now more particularly to Figs. 2 and 3, the conformation of the entering edges of the slides B³ and D², relatively arranged or combined for transferring a plate from the magazine to the plate-holder, will be described. 65 The plate-holder slide has its entering edge beveled on its outer or posterior surface at a convenient angle (say about thirty degrees,

as at B^{2X}) continuously throughout its entire length. Those portions of the entering edge of the slide D² adjacent to the lateral edges 70 of said slide are formed with extensions D^{2X}, projecting beyond the edge of the body portion of said slide and (relatively to the edge of the plate-holder slide B³) beyond the slide B³ when the two slides are combined. These 75 extensions are thickened on their outside surfaces to a thickness equaling that of the two slides when combined. These thickened portions where their surfaces adjoin the beveled edge of the slide B³ conform 80 thereto. From points immediately adjacent to the wedge-shaped edge of the slide B³ these thickened portions D^{2X} of the slide D² are beveled, as at D^{2XXX}, said beveled surface forming with said inner surface of the slide D² a 85 convenient angle, say about thirty degrees. When this combination of slides is thrust inward, the beveled edges D^{2XXX} of these extensions D^{2X} on the slide D² advance in a plane between the foremost plate E^X of the 90 series and the next plate of the series, (see Fig. 3,) whereby the said plate E^X, which by the action of the spring-follower has already been projected into the receiver, is now, along with the receiver, forced into the plate-holder 95 ready for exposure. The remaining portion of the entering edge of the slide D² between the said extensions D^{2X} is beveled from its outside to its inside surface at an angle similar to that of the other bevels. The housings B^{4X} and D^{10X} for the entering edges of the slides B³, D², and D³, respectively, are 100 beveled and recessed, as at B^{4XXX}, Fig. 4, and D^{10XXX}, Figs. 1 and 6, to conform to the extensions D^{2X} and D^{3X}, forming a light-tight 105 joint when the slides are closed.

Now, referring to Figs. 5 and 7, the conformation of the entering edges of the slides B³ and D³, relatively arranged or combined for transferring a plate from the receiver to 110 the magazine, will be described. The entering edge of the plate-holder slide B³ has already been described. Those portions of the entering edge of the slide D³ adjacent to the lateral edges of said slide are formed 115 as extensions D^{3X} beyond the edge of the body portion of said slide, and when in combination the edges of said extensions are beveled in the plane of the bevel of the entering edge of the slide B³, (see Fig. 7,) whereby the entering edges of the slide B³ and of the extensions of the slide D³ form, when in combination, wedges, the edges of which, when the combined slides are forced in, advance in a plane between the plate or film carrier contained in the receiver and the frame of the receiver, so that the plate or film carrier is ejected from the receiver and forced or projected into the magazine. The remaining portion of the entering edge of the slide D³ is 120 beveled from the outside surface of the slide to its inside surface. Thus it will be seen that I have disclosed one form of construction for magazine and plate-holder slides which 125

when combined in one way will serve to inject a plate from the magazine into the holder, and when combined in another way will eject a plate from the holder and transfer it into the magazine. I therefore do not limit my invention to the exact construction shown in this regard, but reserve the right to vary such construction in any manner and to any degree within the skill of persons conversant with the construction of such apparatuses.

Among the important functions performed by the receiver is that of bridging over the space occupied by the slide of the plate-holder, and in case of a removable magazine the additional adjacent space occupied by the slide of the magazine. It is readily apparent that a plate or a plate or film carrier in passing from the magazine to the plate-holder proper would naturally drop by gravity into the said space unoccupied by the said slide or slides when open. I therefore provide a plate-receiver which is to be advanced so as to bridge over said space and to receive a plate or film carrier which is to be transferred from the magazine to the plate-holder proper, or the reverse.

It is apparent that any well-known form of spring may be provided for the follower F, and it is also evident that any other form of follower may be employed, so long as it conforms in size to that of the plate-carriers used in connection therewith.

This being the construction, the operation of my invention is as follows: The plate-holder B is (after the operation of focusing has been performed and the focusing-screen removed) connected with the back frame A of the camera in cases where the invention is applied to cameras of ordinary construction. Where the part B, designated as the "plate-holder," is a part of the camera, then the magazine is removed until after focusing and removal of the focusing-screen, and then the magazine is connected with the plate-holder B proper. The cap or shutter is placed over the lens, and the slides B³ and D² (being coupled together to act as one slide by the locking device) are withdrawn until the stop B^{3x} is reached. The springs F' of the follower F now force the entire series of plate-carriers forward (it being understood that each plate-carrier has a plate or film arranged therein) until the foremost plate-carrier of the series is projected into the plate-receiver C. (See Fig. 3.) The slides are then forced in, when the beveled extensions of the slide D² enter between the foremost and next succeeding plate-carrier of the series and force the receiver, together with the foremost plate thereof, in, into the holder B against the tension of the springs C'. After exposure the magazine D is detached from the plate-holder B, is reversed, and again connected with the holder. In this action the rear slide D² of the magazine is operatively connected with the slide B⁴ of the holder by means of fastening devices, so that both slides act as one. The

slides are now withdrawn, when the springs C' force the plate-holder, together with the plate-carrier therein, against the magazine. The slides are now forced in, the beveled extensions of the slides striking between the beveled edge C^{3x} of the top of the receiver and the rounded edge of the top of the plate-carrier, which is in the receiver, and by the advancement of the slides between the two the plate-carrier is forced into the magazine. When the slides are forced completely in, the magazine is disconnected from the plate-holder, reversed, and again connected, when the next plate in the series of the magazine may be by repeating the operation described exposed.

Having described my invention and its operation, what I claim is—

1. A magazine, in combination with a plate-holder provided with a plate-receiver and an interposed slide for forcing a plate from the magazine into the plate-receiver of the holder, substantially as specified.

2. The combination of a magazine provided with a follower and a plate-holder provided with a plate-receiver, substantially as specified.

3. The combination of a plate-holder with a spring-pressed plate-receiver and with a reversible magazine adapted to receive and deliver plates from and to said receiver, substantially as specified.

4. The combination of a plate-holder, a plate-receiver having flanges, and a magazine provided with a spring-follower, substantially as specified.

5. A plate-holder having a rib, in combination with a slide having an angle-plate to embrace said rib, substantially as specified.

6. A plate-holder provided with a plate-receiver, in combination with a plate-carrier adapted to enter the receiver, substantially as specified.

7. A plate-receiver comprising an open frame having projecting flanges thereon upon two sides and one end thereof, substantially as specified.

8. A plate-holder provided with beveled strips having stops, in combination with a slide having beveled projections, substantially as specified.

9. The combination, with a magazine, of a plate-holder proper and a plate-receiver constructed and arranged to bridge the slide-spaces of the magazine and holder, substantially as specified.

10. The combination of a plate-holder proper and a plate-receiver adapted to cover the slide-space of the holder, whereby the transference of plates from and into the holder is expedited, substantially as specified.

11. In a magazine or plate-holder, a slide for closing the opening of the same provided with beveled edges and extensions, and a housing adapted to receive the same, substantially as specified.

12. A reversible magazine having a continuous opening therethrough and having slides at opposite sides thereof, one of said slides being thickened to form a marginal wedge, substantially as specified.
13. A magazine provided with slides, one of which is extended to form wedges having a surface beveled to conform to the beveled edge of an adjacent slide, substantially as specified.
14. The combination of a plate-holder, having a slide provided with a beveled edge, with a magazine having a slide provided with wedge-extensions, and a fastening device for connecting two slides to operate as one, substantially as specified.
15. The combination, with a magazine hav-
- ing a slide, of a plate-holder having a slide, and a fastening device adapted to fasten the plate-holder slide to the magazine-slide when the latter is unfastened, substantially as specified.
16. The combination, with a plate-holder and a magazine and with the slides thereof, of a fastening device adapted to lock the magazine-slide when said device is operated to unfasten the slides from each other, substantially as specified.

In testimony whereof I affix my signature in presence of two witnesses.

THOMAS S. WILES.
